Primary Examiner — Sandra Snapp*Assistant Examiner* — Elisabeth S Ko(74) *Attorney, Agent, or Firm* — Tutunjian & Bitetto, P.C.(57) **CLAIM**

The ornamental design for a fence gate stabilizer, as shown and described.

DESCRIPTION

FIG. 1 is a top perspective view of the fence gate stabilizer showing my new design;

FIG. 2 is another perspective view of the fence gate stabilizer inverted;

FIG. 3 is a front side view thereof;

FIG. 4 is a left side view thereof;

FIG. 5 is a rear view thereof;

FIG. 6 is a right side view thereof;

FIG. 7 is a top view thereof;

FIG. 8 is a bottom view thereof; and,

FIG. 9 is a plan view showing the fence gate stabilizer in an environment of use.

The broken lines in the drawings are for purposes of showing environment structure and do not make up any part of the claimed invention.

1 Claim, 8 Drawing Sheets(56)
